(57) **CLAIM**

The ornamental design for a tree fastener for use of automobile cavity, as shown and described.

DESCRIPTION

FIG. 1 is a perspective view of the present invention.

FIG. 2 is a front elevational view thereof.

FIG. 3 is a rear elevational view thereof.

FIG. 4 is a bottom-up view thereof.

FIG. 5 is a top-down view thereof; and,

FIG. 6 is a side profile view thereof.

The broken lines in the drawings illustrate portions of the tree fastener for use of automobile cavity and form no part of the claimed design.

1 Claim, 4 Drawing Sheets
